United States Patent Office

Des. 205,988

Patented Oct. 18, 1966

205,988

SIGN HOLDER

Daniel M. McCormick, 7845 Alderman Road,
Jacksonville, Fla.

Original design application July 19, 1965, Ser. No.
86,444. Divided and this application Dec. 20, 1965,
Ser. No. 507

Term of patent 14 years

(Cl. D1—3)

FIG. 1

FIG. 2

FIG. 4

FIG. 3

FIG. 5

FIG. 6

FIG. 8

FIG. 7

FIG. 1 is a front perspective view of a sign holder showing one embodiment of my new design;

FIG. 2 is a front elevational view thereof;

FIG. 3 is a right side elevational view thereof;

FIG. 4 is a rear elevational view thereof;

FIG. 5 is a front perspective view of a sign holder showing another embodiment of my new design;

FIG. 6 is a front elevational view thereof;

FIG. 7 is a bottom plan view thereof; and

FIG. 8 is a rear elevational view thereof.

This application is a division of my co-pending design application Serial No. D. 86,444, filed July 19, 1965. Design application D. 86,444 was a continuation-in-part of my design application Serial No. D. 80,247, filed June 2, 1964 and now abandoned.

I claim:

The ornamental design for sign holder, substantially as shown.
